(57) **CLAIM**

The ornamental design for pair of limb protectors for a pet, as shown and described.

DESCRIPTION

FIG. 1 is a left side perspective view of a back leg limb protector for a pet showing my new design;

FIG. 2 is a left side perspective view of a front leg limb protector for a pet showing my new design;

FIG. 3 is a left side view of the back leg limb protector for a pet;

FIG. 4 is a left side view of the front leg limb protector for a pet;

FIG. 5 is a right side perspective view of the back leg limb protector for a pet;

FIG. 6 is a right side perspective view of the front leg limb protector for a pet;

FIG. 7 is a front view of the back leg limb protector for a pet;

FIG. 8 is a front view of the front leg limb protector for a pet;

FIG. 9 is a back view of the back leg limb protector for a pet;

FIG. 10 is a back view of the front leg limb protector for a pet;

FIG. 11 is a top view of the back leg limb protector for a pet;

FIG. 12 is a top view of the front leg limb protector for a pet;

FIG. 13 is a bottom view of the back leg limb protector for a pet;

FIG. 14 is a bottom view of the front leg limb protector for a pet; and,

FIG. 15 is a left side view of pair of limb protectors for a pet as used on the front and back legs of a dog.

Right side views not shown are mirror images of left side views. The broken line showing of a dog in FIG. 15 depicts environmental subject matter that forms no part of the claimed design.

1 Claim, 5 Drawing Sheets
